FRED A. RIDER, OF WATERTOWN TOWNSHIP, CLINTON COUNTY, MICHIGAN

GAS TANK LOCK

Application filed October 3, 1931. Serial No. 566,647.

This invention relates to locks for tanks or reservoirs and refers more especially to the push type cap for gas tanks of automobiles.

5 Its object is to produce a safety lock for this purpose in which the ignition key may be used to eliminate the hazard of filling a gas tank while the motor is in operation.

A further object is to obviate the attendant's negligence in replacing the cap after filling the tank with gas as the motorist will have to call for the key before the car can be started.

This lock is also a precaution against the 15 stealing of gas.

I do not wish to infer that the lock can only be constructed to admit the ignition key as it may be more advantageous to use other keys.

20 To this end the invention consists in certain novel and useful features of construction and combination of parts as hereinafter described and claimed; and in order that it may be fully understood reference is to be 25 had to the accompanying drawing of which:

Fig. 1 is a side elevation of a gas tank with the cap and lock in use. Fig. 2 is an enlarged bottom view showing the lock as it would look when unlocked and removed.

30 Fig. 3 is a cross section of an enlarged bottom view of the cap when locked, taken on line 3-3 of Fig. 1. Fig. 4 is a cross section taken on line 4-4 of Fig. 3 showing how the tank neck is locked into the cap.

35 Fig. 5 is a cross section taken on line 5-5 of Fig. 3 showing the action limit pin, the ball type pawl or tumbler and the locking plate engaged with the locking ribs of the tank neck.

40 Throughout the description and drawing, the same number is used to refer to the same parts.

This invention consists of a cap 1 having a transverse opening 2 in which locking mechanism body 3 is held central. Locking mechanism body 3 has a flange 4 which is part of lock body 3. Over the lock body 3 is a lock retaining plate 8 having holes 9 which correspond to holes 5 of flange 4 to allow rivets 7 to be inserted and peened over,

thus forming, through rivets 7 one unit comprised of cap 1, lock mechanism body 3 and lock retaining plate 8. Lock retaining plate 8 has two protrusions 10 extending downward thereto and acting as guides when the cap is inserted into tank neck 11. Between tank neck 11 and retaining plate 8 is a cork gasket 12 which has an opening 13 conforming with the shape and surrounds the lower extremity of lock mechanism body 3, and also has openings 14 which fit over guides 10 of retainer plate 8. Between cork gasket 12 and retainer plate 8 is a metal plate 15 substantially the same form as gasket 12, and keeps spring 16, which is between metal plate 15 and retainer 8, from cutting into cork gasket 12. Spring 16 holds gasket 8 securely against tank neck 11 to keep cap from rattling.

In locking body 3 there is a hole 17 in 70 which action limit pin 18 is pressed. Action limit pin 18 extends downward and beyond the surface of lock body 3 sufficiently to enter quadrant groove 19, of lock plate 20, which is the action limit groove. Also in lock plate 75 20 are tumbler holes 21 and 22; 21 being diametrically opposite one end of limit groove 19 and tumbler hole 22 being diametrically opposite the other end of limit groove 19. Diametrically opposite hole 17 in 80 body 3 is tumbler hole 23 in which is tumbler 24, compressing between it and body 3 a spring 25. Spring 25 and ball 24 create an added friction between lock plate 20 and body 3 in that when lock plate 20 is in either 85 the locked or unlocked position ball 24 forced downward by spring 25 partially enters either hole 21 or hole 22 as the case may be, thus keeping lock plate 20 from turning, due to vibration. Lock plate 20 is substantially 90 anchored to the rotary part 26 of the lock by means of screws 27 passing through holes 28 and screwing into threaded holes 29 of rotor 26 as shown in Fig. 5. From lock plate 26, and being diametrically opposite each other, 95 extend two lugs 30 and 31 which when the lock is unlocked come within the limits of guides 10 of retainer plate 8 and allow the cap to be removed from tank neck 11 without lugs 30 and 31 catching on lock rims 32 100

and 33 of tank neck 11 as will be readily understood by referring to Figs. 2 and 5.

To remove the cap the key must be inserted to adjust the lock to dispose the lugs of the rotor plate in a parallel position with guide lugs of the cap after which the cap is free to be removed to give access to the tank or for any other purpose.

From the foregoing it will be apparent that I have produced a gas tank lock which will protect the cap and lock from removal and can be easily and economically applied to the gas tank of any of the approved cars. It is of course apparent that the detailed construction of the lock outside of the fact that it must have a rotating plate such as lock plate 20 may be varied. In fact, it may be of any tumbler type barrel locks now in use. The distinctive features of this lock being that its operative mechanism is within the cap and hence inaccessible to any person lacking the proper key.

Having now described this invention and its operation, what I claim is:—

1. The combination with a tank neck having a locking rim therein, a cap provided with a multiplicity of lugs corresponding with a plurality of grooves or notches in said locking rim, said cap being provided with a lock having a rotating locking plate thereon, said locking plate being provided with a plurality of lugs corresponding with the grooves or notches in the aforesaid locking rim which when adjusted to a locked position will hold the cap firmly against the aforesaid tank neck, the said rotary locking plate being provided with a groove therein taking the form of a quadrant of a circle in which a pin securely mounted in the aforesaid lock may slide.

2. The combination with a tank neck having a rim provided with an annular inwardly projecting portion having spaced recesses, of a cap having a lock extending through the cap, a rotative locking plate attached to the bottom of the lock and adapted to be rotated by the operation of the lock, means comprising a curved slot in the locking plate and a pin on the cap engaging the slot for limiting the rotation of the locking plate, the said cap having downward protrusions engaging said spaced recesses of the rim when the cap is thereon, the said locking plate having outwardly extending lugs constructed to be passed through said rim recesses when the cap is placed on said neck and to be turned beneath said rim by the lock to secure the cap, and spring controlled devices engaging said cap and locking plate in different positions of the locking plate to hold said plate releasable against displacement by jarring movements of the tank.

3. The combination with a tank neck having a rim provided with an annular inwardly projecting portion having spaced recesses, of

a cap having a lock extending through the cap, a rotative locking plate attached to the bottom of the lock and adapted to be rotated by the operation of the lock, means comprising a curved slot in the locking plate and a pin on the cap engaging the slot for limiting the rotation of the locking plate, the said cap having downward protrusions engaging said spaced recesses of the rim when the cap is thereon, the said locking plate having outwardly extending lugs constructed to be passed through said rim recesses when the cap is placed on said neck and to be turned beneath said rim by the lock to secure the cap, the said locking plate having spaced openings, and the said cap being provided with a cavity and a spring and ball therein constructed to press the ball upon the locking plate and into engagement with said openings in different positions of the plate to hold said plate releasable against displacement by jarring movements of the tank.

In testimony whereof, I affix my signature.

FRED A. RIDER.
